SLACK ADJUSTER FOR LOCOMOTIVE ENGINE AND TENDER CONNECTIONS

Filed May 11, 1926

Patented Aug. 31, 1926.

1,598,186

UNITED STATES PATENT OFFICE.

ASHLEY L. WRIGHT, OF AUBURNDALE, MASSACHUSETTS, ASSIGNEE OF ONE-HALF
TO JOHN ELDERT, OF BOSTON, MASSACHUSETTS.

SLACK ADJUSTER FOR LOCOMOTIVE ENGINE AND TENDER CONNECTIONS.

Application filed May 11, 1926. Serial No. 108,329.

This application is a continuation in part of my application entitled Slack adjusters for locomotive engine and tender connections, filed April 15, 1926, Serial No. 102,096.

The invention relates to the tensioned connection between a locomotive and its tender, said connection comprising a draw-bar pivotally connected with the engine, a coupling-pin supported in a fixed position on the tender and engaging a slot in the rear end of the draw-bar, a buffer-carrying arm fixed to the tender, a yielding buffer movable in said arm, and buffer springs carried by the arm and exerting a forward pressure on the yielding buffer, causing the latter to cooperate as usual with the usual non-yielding buffer projecting rearwardly from the engine in tensioning the connection, and preventing objectionable slackness therein.

The object of the invention is to provide for use with a tensioned connection, thus characterized, a simple adjunct or attachment, enabling the buffer springs to be quickly and conveniently re-tensioned by force externally applied and at a minimum expense and loss of running time.

Of the accompanying drawings forming a part of this specification,—

Figure 1 is a top plan view, showing adjacent portions of an engine and its tender, including the usual tensioned connection, and an adjunct associated therewith, embodying the invention.

Figure 2 is a section on the planes indicated by the line 2—2 of Figure 1.

Figure 3 shows in perspective one of the shims hereinafter described.

Figure 4 shows in perspective one of the two rods shown by Figure 1, and in sectional perspective the abutment head hereinafter described, removed from the rod.

Figures 5, 6 and 7 are fragmentary sectional views hereinafter referred to.

Figure 8 is a fragmentary sectional view similar to a portion of Figure 2, showing a modification.

Figure 9 is a view similar to a portion of Figure 2, showing an alternative arrangement.

Figure 10 shows in perspective the shim shown by Figure 9.

The same reference characters indicate the same parts in all of the figures.

In Figures 1 to 7, of the drawings, 12

designates a portion of the fixed breast beam at the forward end of a locomotive tender, this beam supporting the usual vertical coupling-pin 13, which cooperates with the usual draw-bar 14 in connecting the tender with a locomotive engine. The draw-bar is provided with a slot 15 in its rear end portion, and its forward end portion extends under the engine, and is connected with a forward pivot member (not shown) on the framing of the engine, said pivot member, the draw-bar and the pin 13 constituting the usual flexible connection between the engine and the tender, permitting the relative movements thereof required by track curves.

Formed on the breast beam 12 is a central forwardly projecting buffer-carrying arm 16, having in its forward portion a guiding recess 17, in which the hollow shank 18^a of the yielding buffer-head 18 is movable. The inner end face 17^a of the guiding recess constitutes an abutment for the rear ends of the usual springs which back the buffer-head 18. There are usually two pairs of springs, as shown by Figure 2, each pair including an outer helical spring 19 and an inner helical spring 20, the forward ends of the springs of each pair bearing on the buffer-head 18, as shown by Figure 5, when the adjunct hereinafter described is not in use.

The engine frame is provided with a rearwardly projecting buffer-carrying arm 22, to which is fixed the non-yielding buffer of the engine. Said buffer usually includes a base member 23, bolted to the arm 22, and a chafing member or head 24, detachably engaged with the base member 23, as indicated by Figure 2. The head 24 and the head 18 of the yielding buffer of the tender have the usual reciprocal bearing surfaces, one of which has a reentrant, and the other a salient curvature, as shown by Figure 1.

When the engine and tender are in service, it is important that the buffer springs be maintained at a substantially uniform tension, and not be allowed to relax and exert materially less than the predetermined pressure on the buffer-heads 18 and 24, so that there will be no objectionable slackness in the connection.

It is found that the wear caused by the frictional contact between the coupling-pin 13 and the end 15^a (Figure 2) of the draw-bar slot elongates the slot and permits ex-

pansion of the buffer springs, also that the draw-bar is elongated by the tensile strain thereon, the result being a decrease of the spring tension and an undesirable slackness.

The structure above described embodies the usual tensioned connection between the engine and tender, and as heretofore used, does not include means enabling the springs to be compressed by force externally applied, to increase their tension and take up the slackness due to wear of the slot end 15^a and the coupling-pin, and the elongation of the draw-bar due to the tensile strain thereon when in use. In the structure as prepared for operation, the buffer springs bear directly on the buffer-head 18, as shown by Figure 5.

In carrying out my invention, I provide an adjunct or attachment, adapted to be applied to said structure after the above-mentioned wear and elongation have occurred, the adjunct permitting the compression of the springs by force externally applied, and an increase of the tension of the springs in the manner hereinafter described.

Said adjunct includes a pair of abutment heads 28, and a pair of rods 26, engaged with the abutment heads, there being one abutment head and the accompanying rod for each pair of springs. The abutment heads 28 are formed to be inserted in the hollow shank 18^a of the buffer-head 18, and to be interposed between the buffer-head and the outer ends of the springs, as shown by Figure 6. The abutment heads are loosely engaged with the rods 26, preferably by approximately ball-shaped heads 26^a formed on the rods, and sockets 28^a formed in the abutment heads, this engagement permitting the rods to turn in the heads. The rods extend rearward from the abutment heads through orifices 31 (Figure 2) formed for their reception in portions of the arm 16. The rear end portions of the rods 26 are provided with slots 32, to receive wedges 33, adapted to bear on the usual vertical face 16^a of the arm 16, as shown by Figure 2, and confine the rods against forward endwise movement.

The adjunct preferably includes shims 29 which may be disks, as shown by Figure 3, adapted to be inserted in slots 30, formed for their reception in the hollow shank 18^a. When it becomes evident that there is an objectionable slackness in the tensioned connection, the coupling-pin 13 is removed, and the engine is moved forward from the tender far enough to permit the removal of the buffer-head 18 from the arm 16. The abutment heads 28 and rods 26 are then applied, the rods being inserted in the springs and in the orifices 31, their rear ends projecting from the face 16^a, so that the slots

32 are partly exposed at the rear of said face. The buffer-head 18 is then returned to place and bears on the abutment heads. The engine is then backed, while the tender is prevented from backing, and the buffer-head, the abutment heads, and the rods are forced rearward, thus causing a compression of the springs and increasing the exposure of the rod slots 32. The wedges 33 now enter the slots 32 and maintain the compression and tension of the springs, until the engine and tender are again coupled together by the pin 13, the wedges being then removed. The tensioned connection is now conditioned for operation, assuming that the springs have been sufficiently compressed by the abutment heads alone. If, however, further compression of the springs is required, the shims 29 are employed. To permit this employment, the buffer-head 18, which is now loose, is moved forward by hand on the arm 16, and on the abutment heads, without removing the coupling-pin 13, the abutment heads being confined as above described, by the wedges 33. There is at this time, sufficient looseness to permit the buffer-head 18 to be moved forward by hand, far enough to locate the slots in advance of the confined abutment heads, as shown by Figure 7, thus permitting the insertion of the shims 29, between the buffer-head and the abutment heads. The engine is again backed, so that the buffer-head 18 bears on the shims, as shown by Figure 2, and through the shims and the abutment heads, additionally compresses the springs, the wedges 33 entering the slots 32 more deeply and maintaining the additional compression.

The wedges are then removed, so that the connection is conditioned as before, for operation. It is obvious that more than one shim may be employed with each abutment head, and that the shims may be of any desired thickness.

The described loose connection between the abutment heads 28 and the rods 26, prevents liability of breaking the connection between the heads and rods which would exist if the heads were rigidly attached to the rods, the heads being subjected to torsional strain by the springs. Said loose connection permits the rods to be turned in the heads to cause the slots 32 to extend vertically, and thus permit the wedges 33 to descend by gravity in the slots and automatically maintain the increased tension of the springs.

As an equivalent of the wedges 33 as the means for temporarily maintaining the increased tension of the springs, I may employ nuts 33^a engaged with threads on the rear end portions of the rods and adapted to be set up against the end face 16^a, as shown by Figure 8.

In the alternative or modified arrangement shown by Figure 9, the abutment heads, designated by 28^a, are located at the inner ends of the springs, and the rods, 5 designated by 26^a, have rear end faces on which the swivelled foot 40 of a jack-screw is adapted to bear. The jack-screw may bear on a fixed abutment (not shown) on the tender and be operated to force the rods 10 26^a and abutment heads 28^a forward, and thus compress the buffer springs and permit the insertion of shims 29^a in slots 30^a in the arm 16, the springs being additionally compressed by an operation which does not 15 involve the uncoupling of the engine and the application of force by backing the engine as first described. The shims 29^a are provided with recesses 29^b which receive the rods 26^a when the shims are dropped into 20 the slots 30^a. The force applied by the jack-screw compresses the springs to take up looseness due to the wear on the coupling-pin 13 and the draw-bar slot, and elongation of the draw-bar, the compression being 25 maintained by the shims, after the removal of the jack-screw.

As above stated, the described adjunct is not present in the structure as first used. After the adjunct has been installed, it becomes 30 a permanent element of the structure. Said adjunct may, however, be incorporated in the structure at the time of manufacture thereof.

The only adaptation of the previously 35 existing structure required to permit the application of the described adjunct thereto, is the formation of the rod-guiding orifices 31 in the arm 17, and the shim-receiving slots 30 in the shank 18^a of the buffer-head 18.

I claim:

1. In a tensioned connection between an engine and a tender, comprising a draw-bar 45 extending between the engine and tender, a coupling-pin carried by the tender and engaging a slot in the rear end of the draw-bar, a buffer-carrying arm carried by the tender in fixed relation to the coupling-pin, a buffer-head carried by said arm, and springs pressing the buffer-head forward to 50 cause the cooperation of the buffer-head with a rigidly backed buffer-head on the engine and maintain an end of the draw-bar slot in contact with the coupling-pin, the combination with said connection of a spring-tensioning adjunct carried by said arm and comprising abutment heads 55 slidable in the arm, rods engaged with the abutment heads and slidable in guides on the arm, the abutment heads and rods being movable by force externally applied to compress the springs, and shims adapted to confine the abutment heads and rods to maintain the compression of the springs, said adjunct being adapted to be actuated by the

externally applied force to increase the tension of the springs and thereby compensate for wear of the coupling-pin and draw-bar and elongation of the draw-bar.

2. In a tensioned connection between an engine and a tender, comprising a draw-bar 70 extending between the engine and tender, a coupling-pin carried by the tender and engaging a slot in the rear end of the draw-bar, a buffer-carrying arm carried by the tender in fixed relation to the coupling-pin, a buffer-head carried by said arm, and springs pressing the buffer-head forward to 75 cause the cooperation of the buffer-head with a rigidly backed buffer-head on the engine and maintain an end of the draw-bar slot in contact with the coupling-pin, the combination with said connection, of a spring tensioning adjunct carried by said arm and comprising abutment heads slidable in the arm and interposed between the buffer-head and the forward ends of the 80 springs, rods engaged with the abutment heads and slidable in guides on the arm, the buffer-head and the abutment heads being movable by force externally applied to the buffer-head, to compress the springs, and means for temporarily confining the rods with the abutment heads in spring-compressing position, said adjunct being 85 adapted to be actuated by a rearward movement of the buffer-head, to increase the tension of the springs and thereby compensate for wear of the coupling-pin and draw-bar and the elongation of the draw-bar.

3. In a tensioned connection between an engine and a tender, comprising a draw-bar 90 extending between the engine and tender, a coupling-pin carried by the tender and engaging a slot in the rear end of the draw-bar, a buffer-carrying arm carried by the tender in fixed relation to the coupling-pin, a buffer-head carried by said arm, and springs pressing the buffer-head forward to 95 cause the cooperation of the buffer-head with a rigidly backed buffer-head on the engine and maintain an end of the draw-bar slot in contact with the coupling-pin, the combination with said connection of a spring-tensioning adjunct carried by said arm and comprising abutment heads slidable in the arm and interposed between the buffer-head and the forward ends of the springs, rods engaged with the abutment heads and slidable 100 in guides on the arm, the buffer-head and the abutment heads being movable by force externally applied to the buffer-head to compress the springs, means for temporarily confining said rods with the abutment heads spaced from the buffer-head, and separate shims insertible between the abutment heads and the buffer-head, said adjunct being adapted to be actuated by a rearward movement of the buffer-head to increase the tension of the springs and thereby compen- 105 110 115 120 125 130

sate for wear of the coupling-pin and draw-bar and the elongation of the draw-bar.

4. An engine and tender connection embodying the combination specified by claim 3, the buffer-head being provided with slots permitting the insertion of the shims between the abutment heads and the buffer-head.

5. An engine and tender connection embodying the combination specified by claim 3, the rods being provided at their rear end portion with adjustable means adapted

to cooperate with the arm in temporarily confining the rods against forward movement.

6. An engine and tender connection embodying the combination specified by claim 1, the rods being loosely engaged with the abutment heads, so that relative turning movements of the said rods and heads is permitted.

In testimony whereof I have affixed my signature.

ASHLEY L. WRIGHT.
